(57) **CLAIM**

The ornamental design for a utility hex pole, as shown and described.

DESCRIPTION

FIG. 1 is a perspective view of a utility hex pole, showing our new design;

FIG. 2 is an enlarged partial view of the top portion as seen in FIG. 1 thereof;

FIG. 3 is another perspective view of FIG. 1 thereof;

FIG. 4 is a top plan view of FIG. 1 thereof;

FIG. 5 is a bottom plan view of FIG. 1 thereof;

FIG. 6 is a side elevation view of FIG. 1 thereof;

FIG. 7 is an opposite side elevation view of FIG. 1 thereof;

FIG. 8 is a perspective view of FIG. 1 thereof, showing the utility hex pole in use;

FIG. 9 is a perspective view of a second embodiment of the hex pole of FIG. 1 thereof;

FIG. 10 is another perspective view of FIG. 9 thereof;

FIG. 11 is a side elevation view of FIG. 9 thereof; and,

FIG. 12 is an opposite side elevation view of FIG. 9 thereof.

The broken lines in FIGS. 2 and 8 illustrate portions and environment of the utility hex pole which form no part of the claimed design. The bottom plan view for the second embodiment is the same as the bottom plan view shown in FIG. 5, and is therefore not depicted.

The utility hex pole is shown in FIGS. 9-11 with a symbolic break in its length. The appearance of any portion of the article between the break lines forms no part of the claimed design.
